UNITED STATES PATENT OFFICE.

BENJAMIN F. AUGUSTINE, OF BUFFALO, NEW YORK.

ROTARY GAS-ENGINE.

1,382,612.

Specification of Letters Patent. Patented June 28, 1921.

Application filed August 15, 1917. Serial No. 186,416.

To all whom it may concern:

Be it known that I, BENJAMIN F. AUGUSTINE, a citizen of the United States, residing at Buffalo, in the county of Erie and State of New York, have invented certain new and useful Improvements in Rotary Gas-Engines, of which the following is a specification.

The invention relates to gas engines, and more particularly to a two-cycle multiple cylinder rotary gas engine.

An object of the invention is to provide a gas engine of the above type having exhaust ports at the outer end of each cylinder and with air intake ports adjacent the inner end of the cylinder for admitting air for scavenging the cylinder.

A further object of the invention is to provide a gas engine of the above character with fuel intake ports located adjacent said air intake ports and so disposed relative thereto that the air intake ports are opened first to admit a portion of the air before the fuel intake ports are uncovered.

A still further object of the invention is to provide an engine of the above character wherein the cylinders are arranged radially of the axis of rotation of the engine, so that the centrifugal force acting on the gases aids in the scavenging of the cylinder and in the supplying of air and gas to the cylinder.

A still further object of the invention is to provide an engine of the above character having a fuel supply chamber which is substantially surrounded by a chamber for receiving the exhaust gases, so that the fuel will be thoroughly gasified before it enters the cylinders.

A still further object of the invention is to provide an engine of the above type with means for supplying the air first to the crank casing where the bearings for the engine are cooled and the heat from the inner parts of the engine absorbed, before the air is led to the cylinders.

These and other objects will in part be obvious and will in part be hereinafter more fully disclosed.

In the drawings, which show by way of illustration one embodiment of the invention.—

Figure 1 is a vertical sectional view through the engine, taken longitudinally of

the shaft, the bonnet and tubes for the exhaust gases being omitted;

55

Fig. 2 is a transverse vertical sectional view in part through the cylinders and in part through the pumps;

Fig. 3 is a vertical sectional view longitudinally through the casing, but showing the pump cylinders in place;

60 Fig. 4 is an end view of the same;

Fig. 5 is a vertical sectional view, showing a portion of the shaft, one of the heads of the casing, a portion of the casing and two of the pump cylinders;

65 Fig. 5^a is a fragmentary sectional view showing the exhaust outlet;

Fig. 6 is an end view of the head of the engine casing, also showing the shaft in section;

70 Fig. 7 is a side view of the shaft;

Fig. 8 is a transverse sectional view through the shaft and the enlargement thereon;

75

Fig. 9 is a longitudinal sectional view of a portion of the shaft;

Fig. 10 is a view partly in section and partly in plan, of the ported section of the main shaft;

80

Fig. 11 is an end view of the shaft with the balancing plate applied thereto.

The invention consists broadly in a rotating casing mounted to rotate in bearings, and provided with a plurality of radially disposed cylinders. The cylinders are preferably arranged in two rows and are staggered relative to one another. Each cylinder is provided with a piston having a piston rod connection with a fixed crank shaft, so that the cylinders move relative to the pistons and thus cause the casing to rotate about the crank shaft.

85 The engine casing is also provided with a series of pumps, certain of which are used to supply fuel to a fuel chamber disposed within the casing and others of which are used to supply air to the crank casing. The exhaust gases pass out through ports in the ends of the cylinder and are directed to a chamber which surrounds partly or wholly the fuel supply chamber, so that the heat of the exhaust gases may be utilized for thoroughly gasifying the fuel.

90 100 105
Each cylinder is provided with air intake ports which are uncovered by the piston at

- the end of its working stroke. These ports are connected with the crank casing, so that the air in the crank casing placed under compression by the pumps and the heat of 5 the inner parts of the engine, will rush through these air ports into the cylinder and thoroughly scavenge the cylinder, forcing the burnt gases out through the exhaust ports.
- 10 Each cylinder is also provided with fuel intake ports located between the air intake ports and these fuel intake ports are connected with the supply chamber. Said fuel intake ports are so proportioned and located relative to the air intake ports, that air enters the cylinder first and partly completes the scavenging thereof before the fuel enters. At the end of the cylinder there is a reentrant head forming an annular 15 space adapted to receive a sleeve carried by the piston and preferably formed as a part of the piston. This sleeve serves to control the exhaust ports.

Referring more in detail to the drawings, 20 my improved gas engine consists of a main casing 1 having a head 2, provided with a projecting shaft 3 adapted to rotate in a bearing. At the other end of the casing there is a head 4, which has a bearing connection 25 5 with a fixed shaft 6. This fixed shaft 6 extends through the engine casing and has a bearing 7 in the other head of the engine casing. Between the ends of the shaft there is a crank 8. This shaft is fixed 30 or held against rotation and the casing rotates about the shaft. The casing is provided with a series of cylinders 9. These cylinders as clearly shown in Fig. 1, are arranged in two rows and the cylinders in 35 40 the separate rows are staggered relative to one another, as clearly shown in Fig. 2.

The casing is also provided with an opening adapted to receive the cylinder which is held seated in the opening by suitable 45 means. In each cylinder is a piston 10. A piston rod 11 connects each piston with the crank 8.

Each cylinder is provided with fins 12, which assist in keeping the cylinder cool. 50 Above the fins 12 there is a sleeve 13, and above the sleeve 13 is a reentrant head 14. These parts are suitably connected to the cylinder. The reentrant head 14 extends down into the cylinder and a spark plug 15 55 is mounted in this reentrant head. The cylinder wall is provided with exhaust ports 16, which lead to a chamber 17 formed in the sleeve 13.

The sleeves 13 of two adjacent cylinders 60 are connected by a suitable pipe 18, and this pipe 18 has a radially extending portion 19, which connects with a chamber 20 in the engine casing. This chamber 20 is formed by a cylindrical partition 21 preferably cast integral with the casing and lo-

cated a short distance from the outer wall of the casing.

A second circular partition 22 is also preferably cast integral with the casing and forms a fuel supply chamber 23. The fuel supply chamber extends from end to end of the casing and is practically surrounded by the exhaust chamber 20.

Each cylinder is provided with air intake ports 24, which are disposed adjacent the inner end of the working stroke of the piston, so that the piston uncovers these air intake ports. The casing is provided with a series of channels 25 (see Fig. 3), which extend inwardly and connect with the crank 80 casing, so that when the cylinder is in place these channels 25 form a series of passages connecting the air intake ports with the crank casing.

Located between the air intake ports are fuel supply ports 26. These fuel supply ports connect with the passages 27, which in turn, are connected to the fuel supply chamber 23 (see Fig. 2).

The piston is provided with a skirt 28, 90 which extends below the head of the piston and with a sleeve 29 which extends outwardly from the piston head. This sleeve 29 is adapted to run in the space formed between the reentrant head and the inner wall 95 of the cylinder. Said reentrant head has an inwardly projecting flange 30 formed with openings 31 registering with the exhaust ports 17. The sleeve 29 is always above this flange 30.

It will be understood, of course, that the cylinder moves and not the piston, as above noted, and while I have referred to the inner end of the working stroke of the piston, in reality the head of the cylinder is moved 105 away from the piston, and it is this extreme outward movement of the cylinder to which I have referred as the inner end of the working stroke of the piston.

Inasmuch as the sleeve 29 is always in 110 this annular space between the reentrant head and the wall of the cylinder, as the sleeve moves outward relative to the cylinder, the gas trapped in the annular space will be more or less compressed and thus 115 form a perfect seal, preventing any leakage of the gases about the end of the sleeve.

The sleeve is formed with an inwardly extending projection 32, which has a recess for a packing 33. It is noted that this packing 120 is directly above the intake ports in the wall of the cylinder and the sleeve is provided with similar ports adapted to register with the ports in the wall of the cylinder. Just below the piston head there is also a 125 packing 34. The extended skirt 28 covers the intake ports when the cylinder moves to its extreme outer position and prevents any fuel gases from escaping into the crank casing.

From the above it will be apparent that when the piston uncovers the exhaust ports, the exhaust gases are allowed to escape, relieving the pressure in the cylinder. Substantially simultaneously, but slightly after the uncovering of the exhaust ports, the air intake ports are uncovered, which permits air from the crank casing to rush outwardly into the cylinder, forcing the burnt gases outwardly to the end of the cylinder, out through the exhaust ports and back into the exhaust chamber. After a portion of air has been allowed to enter the cylinder, forcing the burnt gases away from the head of the piston, then the fuel supply ports are uncovered and gasified fuel rushes into the cylinder, thoroughly mixing with the air and forming a uniform charge.

The centrifugal force acting upon the burnt gases and also the air and fuel gases, aids in the scavenging of the cylinder and the quick supplying of the cylinder with fresh air and with the rich dry fuel gases.

The exhaust gases pass out through suitable ports 35 to a bonnet 36 and from the bonnet to an exhaust pipe. The fuel is supplied to a supply chamber 23 by a series of pumps. In the drawings I have shown six pump cylinders. Three of these cylinders, those indicated at 37, are utilized for pumping air, while the other three indicated at 38 are utilized for pumping fuel. These cylinders are mounted in the engine casing and project slightly therefrom.

Located within each pump cylinder, is a piston 39. A pitman 40 connects each piston with the fixed crank so that as the engine casing rotates, these pump cylinders will slide on the pistons. Each pump cylinder is provided with a port 41. This port connects with a passage 42 formed in the casing, and said passage 42 registers with a passage 43 formed in the head 4, which closes the engine casing. This head 4 is provided with an opening through which the shaft 6 extends. It is also provided with an enlarged chamber or recess adapted to receive the ported extension or enlargement 44 on the shaft 6.

The passages 43 leading from the ports of the air pumping cylinders 37, are adapted to register with a port 45 formed in the extension or enlargement 44 and this port 45 is connected by a lateral passage 46 with the crank casing, so that when the passages 43 are in register with this port 45, air may be delivered from these cylinders back through these passages into the crank casing.

The passages 43 are also adapted to register with a port 47 on the opposite side of the extension or enlargement 44 from the port 45. This port 47 is connected through a series of openings 48 with an annular pocket or recess 49, which in turn, is connected by means of passages 50 with the atmosphere.

Air is drawn in through the passages 50 through the openings 48 to the port 47 and thence through the passages 43 to the pumps.

It will be understood that the port 47 is of sufficient length so as to connect two passages 43 at the same time. In other words, before one passage 43 leaves this port, another passage 43 makes connection therewith. These passages 43 are connected with this port when the pump cylinders are moving outwardly and the pumps are drawing in air. As a result, some one of the pumps is drawing in air at all times. Likewise the port 45 is of sufficient length to connect two of the passages 43 and, therefore, one of the pumps will be continuously supplying air to the crank casing. It will be understood, of course, that the pump cylinders are cut off entirely for an interval as they pass from one port 45 to the other port 47, so as to prevent any escape of the air from the crank casing. This occurs when the piston and cylinder are passing dead centers so that there is no relative movement between the piston and the cylinder. Furthermore, these ports are of sufficient length so that no vacuum or compression occurs in the pumps. The air is drawn into the pump and transferred to the crank casing where it is put under slight compression. This air passing through the crank casing absorbs heat from the shaft and bearings and the inner parts of the engine not only keeping these parts cool, but also transforming the heat into a working force.

The passages 43 leading from the cylinders 38 are adapted to register with the port 49' formed in the extension or enlargement 44. There is a passage 50' formed in the head 4, which connects with the supply chamber 23, as clearly shown in Fig. 1 of the drawings. At certain times this port 49' connects the passage 50' with the passage 43. At this time the charge of fuel drawn into the pumps is delivered by the pumps through these passages to the fuel supply chamber. At other times the passages 43 are connected with the port 51, which extends down into the shaft and connects with the passage 52.

The fuel is supplied to this passage 52 and is drawn by the pumps out through the passages 43 into the pump cylinders. These ports 49' and 51, like the air ports, are of sufficient length so that the fuel is drawn in continuously by the pumps and transferred to the fuel supply chamber, where it is put under slight compression. They are also of such length that the pump cylinders are neither under compression or under vacuum, but merely operate to transfer the fuel to the supply chamber. The fuel entering the supply chamber is subjected to the heat of the exhaust gases in the chamber surrounding the same, and the moist fuel will be carried by centrifugal force out

against the hot plate forming the outer wall of the fuel supply chamber, where it will be thoroughly gasified.

In the operation of my engine, the fuel 5 gases are taken in cold by the pumps and transferred to the fuel supply chamber. In the fuel supply chamber the gases are heated, absorbing the heat from the exhaust 10 gases and thus transferring this heat back into a working force. The fuel will be thoroughly gasified in this fuel supply chamber and will be thus prepared for the cylinders. This fuel supply chamber for gasifying the 15 fuel and many other parts of the engine are shown, described and claimed in detail in my prior Patent No. 1,229,569, granted June 12th, 1917.

As the engine rotates, first one cylinder 20 and then the adjacent cylinder in the next row will be fired. As the engine is a two-cycle engine, each cylinder is fired during each rotation of the engine. Therefore, in my present engine with twelve cylinders, there will be twelve power strokes for each 25 rotation of the engine.

The exhaust ports are uncovered by the 30 sleeve controlled by the piston, and as soon as these cylinders are relieved from pressure, the air intake ports begin to open, allowing the air in the crank casing to pass into the cylinder, forcing the burnt gases out through the exhaust port and thoroughly scavenging the same. After a certain amount of air has 35 been admitted, then the intake ports are opened, permitting the thoroughly gasified fuel to rush into the cylinder and become mixed with the air, forming a uniform charge. The centrifugal force acting on the burnt gases and on the fuel and the air, aids 40 in quickly scavenging the cylinder and supplying the same with the new charge.

As above noted the air in the crank casing 45 is under slight compression and in order to balance the forces therefrom, I have provided a balance plate 2^a which is fixed to the end of the shaft 6 and has an air tight connection with the head 2. This balance plate is of the same diameter as the extension or 50 enlargement 44 and therefore the force endwise on one head is balanced by the force endwise on the other head.

It is obvious that minor changes in the construction and the arrangement of the parts may be made without departing from 55 the spirit of the invention as set forth in the appended claims.

What is claimed is:

1. A rotary gas engine including in combination a rotating casing, a plurality of 60 cylinders carried thereby, a piston for each cylinder, each cylinder having fuel intake ports uncovered by the piston, independent air intake ports disposed in the region of the fuel intake ports and uncovered by the 65 piston, said air intake ports being larger

than the fuel intake ports and being so disposed as to admit air prior to and during the admission of fuel, and exhaust ports disposed in the opposite end of the cylinder from the air intake ports and means carried 70 by the pistons for controlling the exhaust ports.

2. A rotary gas engine including in combination a rotating casing, a plurality of cylinders carried thereby, a piston for each 75 cylinder, each cylinder having fuel intake ports disposed in the region of the fuel intake ports and uncovered by the piston, said air intake ports being larger than the fuel intake ports and being so disposed as to 80 admit air prior to and during the admission of fuel, each cylinder having a reentrant head at its outer end forming an annular space between the head and the wall of the cylinder, said cylinder having exhaust ports 85 adjacent the reentrant head, and a sleeve carried by the piston and adapted to enter said annular space and control said exhaust ports.

3. A rotary gas engine including in combination a fixed shaft having a crank, a casing mounted to rotate about said shaft, a plurality of radially disposed cylinders carried by the casing, a piston for each cylinder, a pitman connecting each piston with the 90 crank, a reentrant head for each cylinder forming an annular space between the head and the wall of the cylinder, said reentrant head having an inwardly projecting flange, said cylinder and flange having aligned exhaust ports, and a sleeve adapted to enter 95 said annular space and adapted to control the exhaust ports.

4. A rotary gas engine including in combination a fixed shaft having a crank, a casing mounted to rotate about said shaft, a plurality of radially disposed cylinders carried by the casing, a piston for each cylinder, a pitman connecting each piston with the 100 crank, a reentrant head for each cylinder forming an annular space between the head and the wall of the cylinder, said reentrant head having an inwardly projecting flange, said cylinder and flange having aligned exhaust ports, a sleeve adapted to 105 enter said annular space and adapted to control the exhaust ports, said sleeve being connected to and movable with the piston, said cylinder having intake ports at the inner end thereof, and said sleeve having openings 110 adapted to register with said intake ports.

5. A rotary gas engine including in combination a fixed shaft having a crank, a casing mounted to rotate about said shaft, a plurality of radially disposed cylinders carried by the casing, a piston for each cylinder, a pitman connecting each piston with the 115 crank, a reentrant head for each cylinder forming an annular space between the head and the wall of the cylinder, said reentrant head having an inwardly projecting flange, said cylinder and flange having aligned exhaust ports, a sleeve adapted to 120 enter said annular space and adapted to control the exhaust ports, said sleeve being connected to and movable with the piston, said cylinder having intake ports at the inner end thereof, and said sleeve having openings 125 adapted to register with said intake ports.

- and the wall of the cylinder, said reëntrant head having an inwardly projecting flange, said cylinder and flange having alined exhaust ports, a sleeve adapted to enter said 5 annular space and adapted to control the exhaust ports, said sleeve being connected to and movable with the piston, said cylinder adjacent its inner end having fuel intake ports and air intake ports, said 10 sleeve having openings formed therethrough adapted to register with the fuel and air intake ports.
6. A rotary gas engine including in combination a fixed shaft having a crank, a casing 15 mounted to rotate about said shaft, a plurality of radially disposed cylinders carried by the casing, a piston for each cylinder, a pitman connecting each piston with the crank, a reëntrant head for each cylinder 20 forming an annular space between the head and the wall of the cylinder, said reëntrant head having an inwardly projecting flange, said cylinder and flange having alined exhaust ports, a sleeve adapted to enter said 25 annular space and adapted to control the exhaust ports, said sleeve being connected to and movable with the piston, said cylinder adjacent its inner end having fuel intake ports and air intake ports, said sleeve having 30 openings formed therethrough adapted to register with the fuel and air intake ports, said sleeve and piston being provided respectively with recesses located above and below the air and fuel intake ports, and 35 packing rings located in said recesses.
7. A rotary gas engine including in combination a fixed shaft, a casing rotating about said shaft and having two rows of radially disposed cylinders, the cylinders in 40 the rows being staggered relative to each other, a piston for each cylinder, a pitman connecting each piston with the crank in said shaft, each cylinder having a reëntrant head forming an annular space between the 45 head and the wall of the cylinder, said reëntrant head having an inwardly projecting flange, said cylinder and inwardly projecting flange having alined exhaust ports, a sleeve movable in said annular space for controlling 50 the exhaust ports, said sleeve being connected to and movable with the piston.
8. A rotary gas engine including in combination a fixed shaft, a casing rotating about said shaft and having two rows of 55 radially disposed cylinders, the cylinders in the rows being staggered relative to each other, a piston for each cylinder, a pitman connecting each piston with the crank in said shaft, each cylinder having a reëntrant 60 head forming an annular space between the head and the wall of the cylinder, said reëntrant head having an inwardly projecting flange, said cylinder and inwardly projecting flange having alined exhaust ports, a sleeve 65 movable in said annular space for controlling
- ling the exhaust ports, said sleeve being connected to and movable with the piston, said cylinder having air intake ports and fuel intake ports adjacent the inner end thereof and said sleeve having openings adapted 70 to register with the air and fuel intake ports.
9. A rotary gas engine including in combination a fixed shaft, a casing rotating about said shaft and having two rows of 75 radially disposed cylinders, the cylinders in the rows being staggered relative to each other, a piston for each cylinder, a pitman connecting each piston with the crank in said shaft, each cylinder having a reëntrant 80 head forming an annular space between the head and the wall of the cylinder, said reëntrant head having an inwardly projecting flange, said cylinder and inwardly projecting flange having alined exhaust ports, 85 a sleeve movable in said annular space for controlling the exhaust ports, said sleeve being connected to and movable with the piston, said cylinder having air intake ports and fuel intake ports adjacent the inner end 90 thereof and said sleeve having openings adapted to register with the air and fuel intake ports, said air intake ports being proportioned and disposed so as to admit air prior to and during the admission of the 95 fuel gases.
10. A rotary gas engine including in combination a fixed shaft having a crank, a casing mounted to rotate about said shaft, said casing having spaced cylindrical partitions 100 forming an air chamber surrounding the crank, a fuel supply chamber surrounding said air chamber, and an exhaust chamber surrounding said fuel supply chamber, a plurality of radially disposed cylinders carried by the casing and extending through the cylindrical partitions to the air chamber, each cylinder having air intake ports at the inner end thereof, and passages connecting with said air chamber, said cylinder 105 having fuel intake ports at the inner end thereof, and passages connecting said fuel intake ports with the fuel supply chamber, said cylinder having exhaust ports at the outer end thereof, a casing surrounding 110 each cylinder and exhaust ports, a pipe connecting the last named casing with the exhaust chamber whereby the exhaust gases are led from the cylinders to the exhaust chamber.
11. A rotary gas engine including in combination a fixed shaft having a crank, a casing mounted to rotate about said shaft, said casing having spaced cylindrical partitions forming an air chamber surrounding the 115 crank, a fuel supply chamber surrounding said air chamber, and an exhaust chamber surrounding said fuel supply chamber, a plurality of radially disposed cylinders carried by the casing and extending through 120
- 125
- 130

the cylindrical partitions to the air chamber, each cylinder having air intake ports at the inner end thereof, and passages connecting with said air chamber, said cylinder having fuel intake ports at the inner end thereof, and passages connecting said fuel intake ports with the fuel supply chamber, said cylinder having exhaust ports at the outer end thereof, a casing surrounding each cylinder and exhaust ports, a pipe connecting the last named casing with the exhaust chamber whereby the exhaust gases are led from the cylinders to the exhaust chamber, said air and fuel intake ports being controlled by the piston, a sleeve carried by the piston for controlling the exhaust ports, said cylinder having a reentrant head spaced from the wall of the cylinder to receive said sleeve, the exhaust ports being disposed at the inner end of said reentrant head, and means for supplying air to the crank casing and for supplying fuel to said fuel supply chamber. 14. A rotary gas engine including in combination a fixed shaft having a crank, a cas-

12. A rotary gas engine including in combination a fixed shaft having a crank, a casing 20 mounted to rotate about said shaft, said casing having spaced cylindrical partitions forming an air chamber surrounding the crank, a fuel supply chamber surrounding said air chamber, and an exhaust chamber 25 surrounding said fuel supply chamber, a plurality of radially disposed cylinders carried by the casing and extending through the cylindrical partitions to the air chamber, each cylinder having air intake ports 30 at the inner end thereof, and passages connecting with said air chamber, said cylinder having fuel intake ports at the inner end thereof, and passages connecting said fuel intake ports with the fuel supply chamber, 35 said cylinder having exhaust ports at the outer end thereof, a casing surrounding each cylinder and exhaust ports, a pipe connecting the last named casing with the exhaust chamber whereby the exhaust gases are led 40 from the cylinders to the exhaust chamber, said air and fuel intake ports being controlled by the piston, and a sleeve carried 45 by the piston for controlling the exhaust ports, said cylinder having a reentrant head spaced from the wall of the cylinder to receive said sleeve, the exhaust ports being disposed at the inner end of said reentrant head, a series of radially disposed pump cylinders mounted in the casing, a piston 50 for each pump cylinder and means whereby

13. A rotary gas engine including in combination a fixed shaft having a crank, a casing mounted to rotate about said shaft, said casing having spaced cylindrical partitions forming an air chamber surrounding the crank, a fuel supply chamber surrounding said air chamber, and an exhaust chamber surrounding said fuel supply chamber, a plurality of radially disposed cylinders carried by the casing and extending through the cylindrical partitions to the air chamber, each cylinder having air intake ports at the inner end thereof, and passages connecting with said air chamber, said cylinder having fuel intake ports at the inner end thereof, and passages connecting said fuel intake ports with the fuel supply chamber, said 50 55 60 65 115 120 125 130

for each pump cylinder, and means whereby certain of said pumps transfers air to the air chamber and whereby certain of said pumps transfers fuel to said fuel supply chamber.

14. A rotary gas engine including in combination a fixed shaft having a crank, a casing mounted to rotate about said shaft, said casing having spaced cylindrical partitions forming an air chamber surrounding the crank, a fuel supply chamber surrounding said air chamber, and an exhaust chamber surrounding said fuel supply chamber, a plurality of radially disposed cylinders carried by the casing and extending through the cylindrical partitions to the air chamber, each cylinder having air intake ports at the inner end thereof, and passages connecting 115 120 125 130

with said air chamber, said cylinder having fuel intake ports at the inner end thereof, and passages connecting said fuel intake ports with the fuel supply chamber, said 5 cylinder having exhaust ports at the outer end thereof, a casing surrounding each cylinder and exhaust ports, a pipe connecting the last named casing with the exhaust

chamber whereby the exhaust gases are led from the cylinders to the exhaust chamber, and means for supplying air to the crank 10 casing and for supplying fuel to said fuel supply chamber.

In testimony whereof I affix my signature.

BENJAMIN F. AUGUSTINE.
